(57) **CLAIM**

The ornamental design for a portion of a footwear sole, as shown and described.

DESCRIPTION

FIG. 1 is a perspective view of a portion of a footwear sole showing my new design; and,

FIG. 2 is a bottom plan view thereof.

The broken lines showing a shoe sole in both figures represent the environmental context in which the design resides, but they form no part of the claim.

1 Claim, 2 Drawing Sheets

FIG. 2
